CLAIM

I claim the ornamental design for eyeglasses, as shown and described.

DESCRIPTION

FIG. 1 is a perspective view of eyeglasses showing my new design;
FIG. 2 is a top plan view thereof;
FIG. 3 is a bottom plan view thereof;
FIG. 4 is a front elevation view thereof;
FIG. 5 is a rear elevation view thereof;
FIG. 6 is a left side elevation view thereof, the right side elevation view being a mirror image; and,
FIG. 7 is side elevation cross-section view thereof taken along line 7—7 in FIG. 2.

The broken lines are directed to environment and are for illustrative purposes only. The broken lines form no part of the claimed design.

1 Claim, 5 Drawing Sheets
